Primary Examiner — Lauren R Calve

(74) Attorney, Agent, or Firm — Patterson Thuente
 Pedersen, P.A.(57) **CLAIM**

I claim the ornamental design for a garment hanger, as shown and described.

DESCRIPTION

FIG. 1 is a perspective view of a garment hanger.

FIG. 2 is a front view thereof.

FIG. 3 is a rear view thereof.

FIG. 4 is a top view thereof.

FIG. 5 is a bottom view thereof.

FIG. 6 is a left side view thereof; and,

FIG. 7 is a right side view thereof.

The broken line showing of the garment hanger represents portions thereof that form no part of the claimed design.
